OR D 7,034

DESIGN FOR CARPET.

Design No. 7,034, dated December 9, 1873

UNITED STATES PATENT OFFICE.

HARTLEY KNIGHT, OF PHILADELPHIA, PENNSYLVANIA, ASSIGNOR TO JOHN GAY, OF SAME PLACE.

DESIGN FOR CARPET.

Specification forming part of Design No. 7,084, dated December 9, 1873; application filed November 28, 1873.
[Term of Patent 3 years]

To all whom it may concern:

Be it known that I, HARTLEY KNIGHT, of the city of Philadelphia, county of Philadelphia, State of Pennsylvania, have invented and produced a new and original Design for Carpets, of which the following is a specification:

The nature of my design is fully represented in the accompanying photographic illustration, to which reference is made.

I claim as my invention—

The configuration of the design hereunto annexed, when applied to carpeting.

Witnesses: HARTLEY KNIGHT.

W.M. H. HAVERSTICK,
SPENCER ALLEN.
